DESIGN FOR A LIGHTING UNIT

Davis H. Tuck, Redding Ridge, Conn., and John H. Dean, Jackson Heights, N. Y., assignors to Holophane Company, Inc., New York, N. Y., a corporation of Delaware

Application April 23, 1942, Serial No. 106,674

Term of patent 14 years

To all whom it may concern:

Be it known that we, Davis H. Tuck and John H. Dean, citizens of the United States of America and residents, respectively, of Redding Ridge, in the county of Fairfield and State of Connecticut, and of Jackson Heights, in the county of Queens and State of New York, have invented a new, original, and ornamental Design for a Lighting Unit, of which the following is a specification, reference being had to the accompanying drawing, forming a part thereof.

The figure is a perspective view of a lighting unit showing our new design.

The side not shown is substantially a duplicate of that illustrated.

We claim:

The ornamental design for a lighting unit, as shown and described.

DAVIS H. TUCK.
JOHN H. DEAN.
